[57] **CLAIM**

The ornamental design for a lathlike element for sieves, as shown.

DESCRIPTION

FIG. 1 is side view of a lathlike element for sieves showing one side of my new design.

FIG. 2 is a side view of the element of FIG. 1, showing the other side thereof.

FIG. 3 is a top plan view of the element of FIG. 1.

FIG. 4 is a bottom view of the element of FIG. 1.

FIG. 5 is an end view showing the left end of the element of FIG. 1.

FIG. 6 is an end view showing the right end of the element of FIG. 1.

FIG. 7 is a cross section in a larger scale along line VII—VII in FIG. 1.

FIG. 8 is a cross section in a larger scale along line VIII—VIII in FIG. 1.

FIG. 9 is a perspective view showing the same side of the element as FIG. 1.

FIG. 10 is a perspective view showing the same side of the element as FIG. 2.

FIG. 6

FIG. 8

FIG. 1

FIG. 2

FIG. 3

FIG. 4

FIG. 5
